STARTER FOR USE WITH WATER SKIS
Paul L. Cormier, 40 Lincoln St., Spencer, Mass.
Continuation of application Ser. No. 173,173, Feb. 14,
1962. This application Oct. 2, 1964, Ser. No. 403,691
4 Claims. (Cl. 193—35)

This invention relates to a starter for use with water skis and, more particularly, to apparatus arranged to provide initial support and movement for a person who is to be towed on water skis by a motor boat. This is a continuation of my co-pending patent application Serial Number 173,173, filed February 14, 1962.

It will be understood that in the sport of water skiing, the hydrodynamic lift on the skis and the skier does not become sufficiently great to support him on the surface of the water until he has attained a certain critical speed. Since the skier, before he is started, is standing in a fixed position on the shore or on a dock, it is necessary that he be brought from zero speed to the critical speed as quickly as possible lest he sink below the surface of the water, in which event starting would be impossible. If the motor boat starts from zero speed and the cable is maintained in taut condition, the skier accelerates at the same rate as the boat and, if the motor boat does not have sufficient power to accelerate rapidly, the skier will never be able to obtain the critical supporting speed before he sinks into the water. If, on the other hand, the boat circles and moves away from the skier with the rope in a loose condition, the boat attains the taut condition of the rope while moving away from the skier at an appreciable speed; it will then be possible for the boat to accelerate the skier very rapidly. In the past, when this style of starting has been attempted, quite often the skier has been jerked forward, falling on his face; sometimes his arms have been severely damaged by the sudden shock. Furthermore, in many places the shore conditions are not conducive to starting either by rapid acceleration of the boat from zero speed or by the boat picking up the skier "on the fly"; such conditions are those in which the shore is very rocky or the area in front of the pickup start was not free of other boats or swimmers. These and other difficulties experienced with the prior art procedures and apparatus have been obviated in a novel manner by the present invention.

It is, therefore, an outstanding object of the invention to provide a starter for a water skier, which starter may be readily and inexpensively manufactured from easily obtainable materials and which is simple in construction, whereby maintenance problems are reduced to a minimum.

Another object of this invention is the provision of an apparatus for the rapid acceleration of a water skier or the like, which apparatus is readily movable from one place to another.

A further object of the present invention is the provision of a water ski starting apparatus which operates effectively irrespective of whether the skier uses two skis or one ski.

It is another object of the instant invention to provide a starter for a water skier which is extremely safe to use and which will maintain the skis in parallel relationship until the skier has accelerated to a high rate of speed.

It is a further object of the invention to provide an apparatus for safely and effectively guiding a keeled ski during rapid acceleration.

A still further object of this invention is the provision of a water skiing starter which may be used without previous experience or training by beginners and handicapped persons.

With these and other objects in view, as will be ap-

2

parent to those skilled in the art, the invention resides in the combination of parts set forth in the specification and covered by the claims appended hereto.

The character of the invention, however, may be best understood by reference to one of its structural forms as illustrated by the accompanying drawings in which:

FIG. 1 is a perspective view of an apparatus embodying the principles of the present invention;

FIG. 2 is a vertical sectional view of the apparatus taken on the line II—II of FIG. 1;

FIG. 3 is a vertical sectional view of an element of the invention taken on the line III—III of FIG. 4; and

FIG. 4 is a vertical sectional view of the apparatus taken on the line IV—IV of FIG. 2.

Referring first to FIG. 1, wherein are shown the general features of the invention, the starter, indicated generally by the reference numeral 10, is shown as consisting of a main body 11 supported on four legs 12, 13, 14, and 15 and provided with a removable seat 16. The main body 11 is provided with four horizontally-elongated parallel walls or partitions 17, 18, 19, and 21 held together by horizontal cross pieces 22 (see FIG. 2). Between the partitions 17 and 18 are located parallel vertical guide walls 23 and 24 and between the partitions 19 and 21 are located similar parallel vertical guide walls 25 and 26. The bottom edges of all of the guide walls are fastened to and supported by the cross pieces 22. Between each of the partitions 17, 18, 19, and 21 and its closest adjacent guide wall 23, 24, 25, and 26, respectively, is mounted in a row a plurality of rollers 27, which, in turn, are rotatably mounted on transverse shafts 28. Between the partitions 18 and 19, however, extend relatively long rollers 29 mounted on shafts 31. The uppermost point in the periphery of each of the rollers lies slightly above the upper edge of its adjacent guide wall. At its upper edge the guide wall 23 is provided with a flange 32, while the guide wall 24 is similarly provided with a flange 33. The flanges 32 and 33 are directed toward one another and their adjacent edges are parallel vertical planes defining a narrow gap which is slightly larger than the thickness of the keel of a water ski. The guide walls 25 and 26 are similarly provided with flanges 34 and 35 which also define a narrow gap for the keel of a water ski. The inner upper corner of the partition 17 is provided with a rubber cornice strip 36, while a similar cornice strip 37 is attached to the inwardly-directed upper corner of the partition 21. The upper corners of the partition 18 are covered by a U-shaped rubber strip 38, while a similar rubber strip 39 protects the upper edges of the partition 19.

Mounted on the forward ends of the partitions 18 and 19 is a mounting block 41 carrying on its outer surface a metal guide bracket 42 carrying a vertically-slidable stop pin 43 which is locked in a selected vertical position by means of a set screw; the upper end of the stop pin normally resides well above the upper level of the peripheries of the rollers 29 which lie between the partitions 18 and 19.

The leg 13 is formed from metal tubing material and is provided with apertures 44; it is carried for vertical sliding in guide brackets 45 and 46, the lower bracket 46 being provided with an adjusting pin 47 which is engageable with the apertures 44. The brackets 45 and 46 are mounted on a vertical supporting member 48 which is nailed at its upper end to the outer side of the partition 21. From the lower end of the supporting member 48 to the rearward edge of a cross piece 22 extends a brace 49. Similarly, the leg 12 is slidably attached to a supporting member 51 which is provided with a brace 52. A similar method of attachment is provided for the legs 14 and 15 at the rearward end of the main body. As is evident in

FIG. 1, the guide walls 23, 24, 25, and 26 extend rearwardly a considerably greater distance than the partitions 17, 18, 19, and 21.

The seat 16, which is removably supported at the rearward end of the main body, consists of two vertical legs 53 and 54 joined at their upper ends by a horizontal seating member 55, the assemblage being formed into a unitary construction by a brace 56 extending between the legs 53 and 54 and the seating member 55. Fastened to the lower end of the leg 53 on the inner surface is a stop board 57 whose lower edge is generally horizontal and is spaced upwardly from and parallel to the lower edge of the leg 53. A similar stop board 58 is fastened on the inwardly-directed surface of the leg 54 of the seat 16. The stop board 57 rests on the upper surface of the partition 17 while the stop board 58 rests on the upper edge of the partition 21, the legs hanging outside of these partitions and pressing against the outer surfaces thereof to lock the seat in place.

FIG. 3 shows particularly well the manner in which the rollers 27 are formed. In the preferred embodiment the roller is formed by injection molding from a tough abrasive-resistant material, such as nylon, which has the added feature of being self-lubricating in the presence of water. The roller 27 is a generally cylindrical member having an annular recess 59 entering one end and leaving a tubular portion 61 and a hub portion 62 joined by an end web 63. The roller is formed with a horizontal bore 64 through which extends the shaft 28 which, in the preferred embodiment, is formed of stainless steel.

Referring now to FIG. 4, it can be seen that between each pair of the rollers 27 is located a filler bar 65 having a broad upper surface 66 which is horizontal and which is slightly below a horizontal plane tangent to the upper peripheries of the rollers 27. The bar 65 is trapezoidal in cross section and has sloping sides which generally approximate the inclination of the rollers 27 so that it is possible with this shape for the surface 66 to extend from very closely adjacent one roller to very closely adjacent the other roller, leaving only a small gap between the surfaces of the roll and the bar.

The operation of the invention will now be readily understood in view of the above description. The seat 16 is placed upon the main body 11 in a position generally determined by the length of the starting operation which is desired, the proficiency of the skier, and the type of skiing which is to be done. Assuming that the skier is to use two skis, the normal position of the seat would be at the extreme rear end of the main body, but it will be understood that the seat can be moved along the upper edges of the side partitions 17 and 21 to any position intermediate of the ends. One of the skis is placed on the rollers 27 between the partition 17 and the partition 18 with its keel lying in the gap between the vertical edges of the flanges 32 and 33 of the guide walls 23 and 24, respectively. Similarly, the other ski is laid on the upper surfaces of the two rows of rollers 27 which lie between the partitions 19 and 21 with its keel lying in the narrow gap between the vertical edges of the flanges 34 and 35 associated, respectively, with the guide walls 25 and 26. It will be understood that the space between the facing surfaces of the partitions 17 and 18 is somewhat larger than the width of a water ski, while the space between the facing surfaces of the partitions 19 and 21 is of the same size.

The skier sits on the seat 16 and places his feet in the harness of the skis. It will be understood, therefore, that the rear ends of the skis will extend in between the legs of the seat and substantially rearwardly of the seat itself. In some positions of starting, therefore, the rearward extensions of the guide walls will be used. The skier then grasps the free end of the towing rope, the other end of which is attached to the motor boat, and the motor boat proceeds forwardly. It will be understood, of course, that the motor boat can start from zero speed with the rope taut. The boat can also swing around in a loop in such

a way that the rope is loose until the boat is moving directly away from the skier, so that the motor boat is going at a substantial speed when the rope is finally drawn taut. With this last procedure the acceleration of the skier, of course, is much faster. In any event, the forward pull of the motor boat causes the skier to be pulled forwardly off the seat 16 and the skis will roll over the upper peripheries of the rollers 27. Eventually, the skier and the skis will leave the forward end of the main body (which is located either in or closely adjacent to the water) and by that time the speed of the skier is great enough to set up the hydrodynamic forces necessary to support him on the surface of the water.

When the type of skiing involves the use of one ski or the so-called "slalom" skiing, it is very difficult to start with only the one ski, so a small balance ski is used. This ski is placed in the space between the partitions 18 and 19 resting on the rollers 29. The small balance ski is quite short and is provided with an easily releasable harness. The skier's left foot is placed in the slalom ski which lies in the space between the partitions 19 and 21, while his right foot rests on the balance ski. When the motor boat pulls the skier forward, eventually the balance ski reaches the front end of the main body 11 and strikes the stop pin 43. The skier with his slalom ski continues to move forwardly onto the water, while the balance ski remains behind nestled against the stop pin.

The partitions, guide walls, and the main structural members of the main body may be formed of wood or they may be formed of a more durable waterproof plastic. The fact that the rollers are mounted on stainless steel shafts assures that the shaft surface will remain smooth and the roller will always rotate freely on the shaft. This is particularly true, if (as in the preferred embodiment) the rollers are formed of nylon. A little water splashed over the surface of the apparatus will provide the water lubrication necessary to cause the rollers 27 to rotate very freely on their shafts.

The cornice strips 36 and 37 associated with the partitions 17 and 21 as well as the rubber strips 38 and 39 mounted in the upper edges of the partitions 18 and 19 serve to protect the skier from splinters and sharp edges. In the same way, the filler bars 65 prevents the edge of a ski or the like from catching between the rollers.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. A starter for use with water skis having keels, comprising a main body of rectangular form which is generally elongated in one direction, a plurality of vertical legs attached to the main body and vertically adjustable relative thereto, two guides mounted on the body, each guide consisting of two parallel rows of rollers extending in the said one direction, a filler bar extending between each adjacent pair of rollers in the same row, each bar having a generally flat upper surface which lies below the tops of the rollers and which extends from closely adjacent the surface of one roller to closely adjacent the surface of the other, each guide being provided with two parallel partitions facing each other from opposite sides of the rows of rollers and extending above the rollers a substantial distance, the rows of each guide being separated by a gap, each roller being mounted for rotation on a horizontal axis extending transversely of the said one direction, guide means associated with the said gap to engage the sides of the keel and to restrict the movement of the ski to the said one direction, the said guide means consisting of two parallel walls having upper edges that are below the tops of the rollers, a flange extending from the top edge of each wall toward the other, the flanges

having adjacent edges defining the said gap, and a seat whose position along the main body is adjustable, the seat having a horizontal seating member which overlies and extends across the two guides.

2. A starter for use with water skis having keels, comprising a main body of rectangular form which is generally elongated in one direction, two guides mounted on the body, each guide consisting of two parallel rows of rollers extending in the said one direction, a filler bar extending between each adjacent pair of rollers in the same row, each bar having a generally flat upper surface which lies below the tops of the rollers and which extends from closely adjacent the surface of one roller to closely adjacent the surface of the other, each guide being provided with two parallel partitions facing each other from opposite sides of the rows of rollers and extending above the rollers a substantial distance, the rows of each guide being separated by a gap, each roller being mounted for rotation on a horizontal axis extending transversely of the said one direction, guide means associated with the said gap to engage the sides of the keel and to restrict the movement of the ski to the said one direction, the said guide means consisting of two parallel walls having upper edges that are below the tops of the rollers, a flange extending from the top edge of each wall toward the other, the flanges having adjacent edges defining the said gap, and a seat whose position along the main body is adjustable, the seat having a horizontal seating member which overlies and extends across the two guides.

3. A starter for use with a pair of water skis, each ski having a keel, comprising a main body which is generally elongated in one direction, two guides mounted on the body, each guide consisting of two parallel rows of rollers extending in the said one direction, the rows of each guide being separated by a gap, each roller being mounted for rotation on an axis at a right angle to the

said one direction, and guide means associated with the said gap to engage the sides of the keel and to restrict the movement of the ski to the said one direction, and a seat whose position along the main body is adjustable, the seat having a horizontal seating member which overlies and extends across the two guides.

4. A starter for use with a pair of water skis, each ski having a keel, comprising a main body which is generally elongated in one direction, two guides mounted on the body, each guide consisting of two parallel rows of rollers extending in the said one direction, the rows of each guide being separated by a gap, each roller being mounted for rotation on an axis at a right angle to the said one direction, and guide means associated with the said gap to engage the sides of the keel and to restrict the movement of the ski to the said one direction, and a seat having a horizontal seating member which overlies and extends across the two guides.
